UNITED STATES PATENT OFFICE.

NATHAN M. LOWER, OF PITTSBURGH, PENNSYLVANIA, ASSIGNOR TO LOCOMOTIVE STOKER COMPANY, OF SCHENECTADY, NEW YORK, A CORPORATION OF PENNSYLVANIA.

LOCOMOTIVE-STOKER.

1,371,252.

Specification of Letters Patent. Patented Mar. 15, 1921.

Application filed September 26, 1914, Serial No. 863,622. Renewed December 27, 1920. Serial No. 433,560.

To all whom it may concern:

Be it known that I, NATHAN M. LOWER, a citizen of the United States, and resident of Pittsburgh, county of Allegheny, and 5 State of Pennsylvania, have invented certain new and useful Improvements in Locomotive-Stokers, of which the following is a specification and which are illustrated in the accompanying drawings, forming a part 10 thereof.

The invention relates to mechanical stokers for locomotives, and more particularly to the means for transferring fuel from the locomotive tender, elevating it, and delivering it to the fire-box of the locomotive, and to mechanism for operating the transferring and elevating means.

The object of the invention is to provide simple and effective apparatus of the general character described, which shall occupy 20 but small space and be easily operated and regulated. A further object is to provide simple and efficient means for arresting extraneous matter which may be intermixed 25 with the fuel, and for reducing the fuel to suitable size.

The invention consists of various parts and arrangement of parts as hereinafter described, and as shown in the accompanying 30 drawings, in which—

Figure 1 is a detail longitudinal vertical section through the rear portion of a locomotive and the forward portion of its tender, some portions of the stoker mechanism being 35 shown in section and some portions in elevation;

Fig. 2 shows in outline the rear end of a locomotive and in vertical section the elevating portions of the stoker mechanism, the 40 motor for driving the stoker being shown in elevation;

Fig. 3 is a detail vertical section of a portion of one part of the elevating mechanism and the regulating means therefor;

Fig. 4 is a sectional detail on the line 45 4—4 of Fig. 1;

Fig. 5 is a transverse section on the line 5—5 of Fig. 4;

Figs. 6 and 7 are similar views showing 50 the parts in different positions;

Fig. 8 is a sectional detail on the line 8—8 of Fig. 2;

Fig. 9 is a sectional detail on the line

9—9 of Fig. 1; and Fig. 10 is a detail section on the line 10—10 of Fig. 1. 55

The cab of a locomotive is represented at 15, the rear wall of its fire-box at 16, and its deck floor at 17. The forward end of a locomotive tender is shown at 18, and its deck or shovel floor at 19. A fuel-receiving 60 hopper 20 is adapted to be located below the deck of the tender and to receive fuel through a suitable opening therein. For convenience in feeding the hopper the floor opening in the deck 19 is covered by a plurality of movable plates, as 21, 22 and 23. By removing one of the plates or by shifting the position of the plates the fuel may be fed to any portion of the hopper.

From the forward end of the hopper, and 70 preferably formed integral therewith, there projects a transfer tube 24, the forward end of which is located below the locomotive deck 17, and is connected with a receiving chamber 25. A plurality of elevating tubes, here 75 shown as two in number and designated 26, 27, lead upwardly from the chamber 25, preferably diverging, as shown. Discharge conduits 28, 29, lead laterally from the upper ends of the tubes 26, 27, and through the 80 rear wall 16 of the fire-box. These conduits may be equipped with any desired form of injecting means for scattering or otherwise distributing the fuel over the grate of the fire-box. As such injecting devices form 85 no part of the present invention they are not shown.

A screw conveyer, shown as comprising two sections 30, 31, mounted upon a single shaft 32, is located within the hopper 20 and 90 transfer tube 24. This conveyer is shown as non-continuous or sectional, for the purpose of providing space for a plurality of vanes 33 carried by the shaft and co-operating with a plurality of fingers 34 for crushing 95 the fuel, and for stopping any extraneous material of large size, such as pieces of metal which may inadvertently be intermixed therewith; these vanes being made of such strength that they will either reduce 100 any such material or will stop the driving motor, in which event the operator will remove by hand the clogging material.

To facilitate this removal the fingers 34 project through suitable apertures in the 105 shell of the hopper 20, and are carried by a

rocker shaft 35, journaled parallel with the tube 24 and provided at its forward end with a crank-arm 36, to which there may be applied a suitable tool, such as the lever 5 used for shaking grates, the deck of the locomotive being slotted for its insertion. A suitable hand controlled latch 37 may be provided for holding the rocker shaft 35 and the fingers 34 stationary. These fingers 10 may be L-shaped, as shown, and so disposed that the crushing force is applied to them upon a radius of the rocker shaft so that it has no tendency to turn the shaft. The material will be forced past the crushing mechanism by the action of the section 15 30 of the transferring screw, but preferably the vanes 33 have inclined faces for the purpose of contributing to the advance movement.

20 Within the tubes 26, 27, there are located screw conveyers 38, 39. The receiving chamber 25 is preferably of small capacity, so that the material advanced by the screw 31 is forced into the lower ends of the tubes 25 26, 27, whereby the transferring screw assists the elevating screws in the performance of their function, overcoming the tendency of the material to rotate about the axes of the latter without advancing, due to its 30 weight and the frictional resistance.

In order to permit the relative movement of the locomotive and tender in all directions, due to inequalities in the track and to the draw-bar action, without injury to the 35 transfer mechanism carried in part by both, the hopper is supported in a suitable swinging stirrup 40; the forward end of the tube 24 is united to the casing of the receiving chamber 25 by a ball and socket joint 41, 40 and the shaft 32 is provided with a universal joint 42.

The conveying and elevating screws may be driven, either continuously or intermittently, by any suitable motor, and there is 45 shown for this purpose a reciprocating engine 43, served with steam through a pipe 44. Preferably the intermittent action of the mechanism is employed, and suitable mechanism for securing such action is shown 50 in the drawings. The piston rod 45 of the motor is provided with a gear rack 46, which reciprocates in suitable ways, as 47, and meshes with spiral pinions 48, 49, fixed, respectively upon the lower ends of the shafts 55 50, 51, journaled upon the axes of the tubes 26, 27. One set of gear teeth on the rack 46 meshes with a pinion 52 loosely mounted on the forward end of the shaft 32, and driving this shaft through the medium of a 60 spring pawl 53, carried by the pinion and a co-operating ratchet wheel 54 keyed to the shaft. The shafts of the elevating screws 38, 39, are tubular, and are sleeved upon the shafts 50, 51, which are in driving connection therewith through the medium of suit-

able pawl and ratchet mechanism, as herein-after described.

In the case of the screw 39 a simple form of ratchet mechanism is employed, as illustrated in Fig. 8, consisting of a crank arm 70 55 keyed upon the upper end of the shaft 51, a pawl 56 pivoted at 57 to the crank arm, a ratchet wheel 58 fixed upon the tubular shaft 59 which carries the screw 39 of the conveyer or elevator, and a spring 60 anchored to the crank-arm and holding the pawl in engagement with the ratchet. This pawl and ratchet mechanism is located at the upper end of the elevator, and is inclosed within a casing 61.

The conveyer or elevator 38 is shown as of larger size than the elevator 39, and hence, when driven at the same speed, has a larger capacity, and is capable of taking up more than one half of the fuel delivered 85 by the conveying or transfer screw. As the two elevators receive from the same chamber and remove the fuel as rapidly as it is delivered thereto, the work performed by each may be varied by the regulation of one. By varying the action of the larger elevator 90 the work performed by both may be made equal; or by reducing or increasing the effectiveness of the larger elevator more or less work may be imposed upon the smaller. 95 The regulation of the delivery to different zones of the fire box is thereby effected. To this end an adjustable pawl lifter is provided in connection with the ratchet mechanism for driving this elevator, whereby the 100 screw may be actuated during the complete power stroke of the rack bar 46, or during only a portion thereof.

The ratchet mechanism associated with this larger elevator is illustrated in Figs. 4, 105 5, 6 and 7. A crank-arm 62 is keyed upon the shaft 50 at the upper end of the tube 26. A pawl 63 is pivoted at 64 to the arm 62, and co-operates with a ratchet wheel 65 fixed upon the upper end of the tubular 110 shaft 66 which carries the elevating screw 38. A spring 67, anchored upon the crank-arm 62, is attached to a post 68 rising from a lug 69 on the pawl 63 and projecting beyond the end of the arm 62. The rocking 115 of the pawl upon the pivot 64 will carry the post 68 across the center line of the crank-arm and to the opposite sides of the center of the pivot 64, whereby the pawl is held, by the action of the spring, either in or out 120 of engagement with the ratchet wheel.

The trip or pawl lifter comprises a lug 70, rising from an arm 71 carried by an annulus 72 turning about a hub on the cap 73 which covers the upper end of the tube 26. 125 A handle 74, fixed to an arm 75 projecting from the annulus 72, affords means for oscillating the latter to move the trip lug 70 to the desired position. A spring latch 76, carried by the arm 75, co-operates with a quad- 130

rant 77 formed on the cap 73 for holding the stop lug 70 in the position to which it may be adjusted.

The pawl 63 is provided with a pair of cam shoulders 78, 79, located upon opposite sides of the pivot 64 and coöperating with the stop lug 70. As the pawl is advanced, being in engagement with the ratchet, its cam shoulder 79 on the forward side of the pivot passes inside of the stop lug 70. The rearward cam shoulder 78, however, engages the stop lug, swinging the pawl on its pivot and disengaging it from the ratchet, the spring 67 completing the swinging movement of the pawl to carry the cam shoulder 78 inside of the arc on which the stop lug 70 is located, and carrying the cam shoulder 79 across this arc. Thereupon the elevator screw comes to rest, the further advance 20 movement of the shaft 50 being without load. Upon the retraction of the pawl by the turning of the shaft 50 in the opposite direction, the cam shoulder 78 passes inside of the stop lug 70, but the cam shoulder 79 25 engages this lug and the pawl is thereby swung to throw its nose toward the ratchet, and this movement is completed by the action of the spring 67. Upon the further retrograde movement of the shaft 50 the pawl clicks over the ratchet teeth. By the manipulation of the handle 74, therefore, the travel of the elevating screw may be varied through a considerable range for the purpose of regulating the quantity of fuel 30 delivered to the fire-box thereby without manually changing the action of the driving motor.

In order to maintain a uniform rate of delivery of fuel from the tender to the fire box a suitable governor is provided for regulating the engine, and is provided with means for varying its governing action whereby the rate of fuel delivery may be controlled. The governor is here shown as 40 comprising a pair of weights 80, 81, pivotally mounted upon the upper end of the shaft 50, and a circumferentially channelled sleeve 82 slidably mounted on the shaft and held in engagement with lugs 83, 84, on the 45 weights by means of a spring 85 reacting against a nut 86, by means of which its tension may be adjusted for varying the speed at which the governor will act. A lever 87, pivotally mounted upon the cap 88 which 50 incloses the ratchet and governing mechanism, is provided with a yoke 89 engaging the channel of the sleeve 82, the outer end of the lever being attached to the stem 90 of a valve in the steam pipe 44. Should the 55 speed of the shaft 50 increase beyond the desired rate, the centrifugal action of the governing weights reduces the steam supply, checking the speed. This acceleration of speed is apt to occur when the ratchet is

tripped early in the stroke and the load 65 upon the motor thereby reduced.

As the engine actuates the conveying and elevating means in one direction of piston stroke only the action of the screws is intermittent. When the steam is throttled by 70 the governing valve the engine strokes are slower, as more time is required to fill the cylinder, though the range of movement of the conveying screw and consequently the amount of fuel advanced to the elevating 75 screws, by each piston stroke are constant at all engine speeds.

While I have shown and described an operative embodiment of the invention and the most desirable construction at this time 80 known to me, various changes may be made without departing from the scope of the invention. While there is shown mechanism for driving the transfer and elevating screws intermittently, various features of 85 the invention are not dependent upon this action but may be employed in connection with other types of motors and transferring mechanism.

I claim as my invention:

1. In a locomotive stoker, in combination, fuel transfer mechanism adapted to be located below the deck of a locomotive and its tender, a plurality of elevating means receiving from the transferring mechanism 95 and adapted to deliver fuel to the fire-box of the locomotive, and means for relatively varying the action of the elevating means.

2. In a locomotive stoker, in combination, fuel transfer mechanism adapted to be located below the deck of a locomotive and its tender, and a plurality of elevating means differing in capacity, receiving from the transferring mechanism and adapted to deliver fuel to the fire-box of the locomotive, 100 and means for varying the action of the elevating means of greater capacity.

3. In a locomotive stoker, in combination, a receiving chamber adapted to be located below the deck of a locomotive, transfer 110 mechanism for delivering fuel to the chamber under pressure, and a plurality of screw elevators leading from the chamber and adapted to deliver independently to the locomotive fire-box, and located outside 115 thereof.

4. In a locomotive stoker, in combination, a pair of elevators differing in capacity adapted to deliver fuel to the fire-box of a locomotive, and means for varying the relative rate of delivery thereby.

5. In a locomotive stoker, in combination, a pair of elevators differing in capacity adapted to deliver fuel to the fire-box of a locomotive, and means for varying the rate 120 of delivery of one of the elevators.

6. In a locomotive stoker, in combination, a pair of elevators differing in capacity

- adapted to deliver fuel to the fire-box of a locomotive, and means for varying the rate of delivery of the elevator of the larger capacity.
5. 7. In a locomotive stoker, in combination, a transferring screw, an elevating screw receiving from the transferring screw, a single power-actuated reciprocating rack-bar, and gears associated with the two screws and meshing with the rack-bar.
10. 8. In a locomotive stoker, in combination, a rotatable element for elevating fuel, an oscillatable shaft, a ratchet wheel mounted with the rotatable element, an arm fixed on the oscillatable shaft, a pawl pivoted to the arm, and coöperating with the ratchet, a retractile spring attached to the arm and to the pawl on radially opposite sides of the pivot of the latter, shoulders on the pawl 15 on circumferentially opposite sides of its pivot, and a trip engageable by said shoulders in alternation for rocking the pawl on its pivot.
15. 9. In a locomotive stoker, in combination, a rotatable element for elevating fuel, an oscillatable shaft, a ratchet wheel mounted with the rotatable element, an arm fixed on the oscillatable shaft, a pawl pivoted to the arm, and coöperating with the ratchet, a retractile spring attached to the arm and to the pawl on radially opposite sides of the pivot of the latter, shoulders on the pawl 20 on circumferentially opposite sides of its pivot, and an adjustable trip engageable by said shoulders in alternation for rocking the pawl on its pivot.
25. 10. In a locomotive stoker, in combination, a screw conveyer, revolving crusher vanes receiving from the conveyer, stationary abutments located between the vanes, means for withdrawing the abutments from such position and means for delivering fuel from such crusher mechanism to the fire-box of a locomotive.
30. 11. In a locomotive stoker, in combination, a screw conveyer, revolving crusher vanes receiving from the conveyer, a rocker shaft parallel with the conveyer, abutments carried by the shaft and extending into the 35 spaces between the vanes and means for delivering fuel from such crusher mechanism to the fire-box of a locomotive.
35. 12. In a locomotive stoker, in combination, a screw conveyer, revolving crusher vanes receiving from the conveyer, a rocker shaft parallel with the conveyer, abutments carried by the shaft and extending into the spaces between the vanes, means for rocking the shaft, and means for delivering fuel 40 from such crusher mechanism to the fire-box of a locomotive.
40. 13. In a locomotive stoker, in combination, a screw conveyer, revolving crusher vanes receiving from the conveyer, a rocker shaft parallel with the conveyer, abutments 45 carried by the shaft and extending into the spaces between the vanes, means for rocking the shaft, and means for delivering fuel from such crusher mechanism to the fire-box of a locomotive.
45. 14. In a locomotive stoker, in combination, means for transferring fuel from the locomotive coal bin, a plurality of elevating means receiving from the transferring means 50 and of combined capacity as great as that of the transferring means, and means for varying the relative effective action of the elevating means.
50. 15. In a locomotive stoker, in combination, means for transferring fuel from the locomotive coal bin, a plurality of elevating means receiving from the transferring means 55 and of combined capacity as great as that of the transferring means and means acting upon one of the elevating means for varying the relative effective action of the elevating means.
55. 16. In a locomotive tender, in combination, a transferring screw conveyer having a gear wheel on the forward end of its shaft, an elevating screw conveyer receiving from the transferring conveyer, a shaft projecting from the lower end of the conduit of the elevating screw, a gear on such shaft, a rack 60 bar meshing with the two named gears, and means for actuating the rack bar.
60. 17. In a locomotive tender, in combination, a transferring screw conveyer having a gear wheel on the forward end of its shaft, an elevating screw conveyer receiving from the transferring conveyer, a shaft projecting from the lower end of the conduit of the elevating screw, a gear on such shaft, a rack bar meshing with the two named gears, 65 and a reciprocating motor for actuating the rack bar.
65. 18. In a locomotive stoker, in combination, a transferring screw conveyer, a pair of elevating screw conveyers receiving therefrom, the drive shafts of each of the contiguous ends of the casings thereof, a gear mounted on the projecting end of each of such shafts, a rack bar meshing with all of 70 said gears, and means for actuating the rack bar.
70. 19. In a locomotive stoker, in combination, a transferring screw conveyer, a pair of elevating screw conveyers receiving therefrom, the drive shafts of each of the contiguous ends of the casings thereof, a gear mounted on the projecting end of each of such shafts, a rack bar meshing with all of 75 said gears, and a reciprocating motor for actuating the rack bar.
75. 20. In a locomotive stoker, in combination, a transferring screw conveyer, an elevating screw conveyer receiving therefrom,

a pair of gears, ratchet and pawl connection between each of the gears and the shaft of one of the named conveyers, a rack bar meshing with the two gears, and means for actuating the rack bar.

5 21. In a locomotive stoker, in combination, a transferring screw conveyer, a pair of elevating screw conveyers receiving from the transferring conveyer, wheels associated

one with each of the several conveyers and 10 having ratchet and pawl connection with the shaft thereof, a rack bar meshing with each of the gears, and means for actuating the rack bar.
